UNITED STATES PATENT OFFICE.

WILLIAM KANE, OF NORRISTOWN, PENNSYLVANIA.

DIRT-REMOVING MEANS.

1,250,469.

Specification of Letters Patent. Patented Dec. 18, 1917.

Application filed May 26, 1917. Serial No. 171,282.

To all whom it may concern:

Be it known that I, WILLIAM KANE, a citizen of the United States, residing at Norristown, in the county of Montgomery and State of Pennsylvania, have invented 5 certain new and useful Improvements in Dirt-Removing Means, of which the following is a specification.

My invention consists of improved dirt 10 removing means, one of its objects being to prevent the accumulation of dirt in the combustion chambers of furnaces.

Another object is to so construct my invention that it will efficiently cool the dirt 15 before and during its discharge.

A further object is to so make my invention that it can be easily controlled and will not interfere with the operation of the boiler.

20 A still further object is to make my invention of comparatively simple construction and so that it can be applied to furnaces of various types.

These objects, and other advantageous 25 ends which will be described hereinafter, I attain in the following manner, reference being had to the accompanying drawings in which

Figure 1 is a longitudinal section of a 30 boiler and furnace of a well known type and having my invention illustrated in connection therewith.

Fig. 2 is a transverse section on the line 2—2 of Fig. 1.

35 Fig. 3 is a fragmentary sectional plan view on the line 3—3 of Fig. 1.

Referring to the drawings, 1 represents a boiler mounted over a furnace including a fire box 2 and combustion chamber 3, a 40 wall 4 extending transversely of the boiler casing 5. The products of combustion pass from the fire box 2 and between the top of the wall 4 and baffle 6 located on the bottom of the boiler 1. I form the combustion 45 chamber 3 with an inclined bottom 7 and inclined sides 8 and 9, the latter being clearly illustrated in Fig. 2. The sides 8 and 9, and the bottom 7, slant toward a common opening 10 at the bottom of the 50 combustion chamber.

A spout 11, preferably made of metal, has one end registering with the opening 10 and is tapered toward its opposite end as illustrated at 12. The spout 11 is curved 55 throughout its length so that while the wide end is substantially horizontal, the narrow

end is arranged vertically and opens into a pit 13 under the furnace structure and into this pit is discharged the dirt from the combustion chamber 3 as will be hereinafter 60 more fully described.

A main supply pipe 14 leads upwardly from a position outside of the furnace and connects with another pipe 15 which, throughout its length is curved around the 65 spout 11 as clearly shown in Fig. 5. The free end 16 of this pipe 15 is preferably closed by a cap 17 and leading from the pipe 15 at different points throughout its length are a plurality of branch pipes 18. 70

Each of the branch pipes 18 has a row of jet tubes 19 which extend through holes in the spout 11, the inner ends of these tubes 19 preferably made flush with the inner surface of the spout 11 and certain of these 75 tubes extend downwardly while others extend upwardly.

Referring to Fig. 1, it will be noted, for example, that the tubes 20 extend downwardly and that the tubes 21 extend upwardly, the intermediate tubes 22 extending substantially horizontal. 80

Steam, air, or other fluid under pressure is supplied to the pipe 14 and is distributed to the respective jet tubes through the medium of the curved pipe 15 and the branch pipes 18. The hot dirt dropping into the combustion chamber 3, will be deflected by the inclined bottom 7 and sides 8 and 9 into the spout 11 and the fluid as it is ejected 85 from the tubes 19, will cool and force the dirt toward the end 12 of the spout 11. The end 12 of the spout is normally closed by a door 23, this door resting upon a ledge 24. 90

A rail 25 is provided to form a guide-way 95 for the upper edge of the door 23 to permit the latter to be slid in front of and away from the end 12 of the spout 11. The rail 25 has a depending portion 26 as illustrated in Fig. 2, and this portion forms an abutment to stop the door when it has been moved in front of the end 12 of the spout 11. A hand lever 27 is pivotally mounted outside of the furnace casing and a link rod 28 pivotally connects the lower end of the 100 lever 27 with the door 23, so that by the movement of the lever 27, the door can be manually moved into an open or closed position. 105

The door 23 can be opened from time to 110 time and the fluid under pressure can be permitted to pass through the pipe 14 by

the operation of a valve 29 which is in convenient reach of a person while standing near the lever 27, so that with one hand the lever 27 can be operated to open the door, 5 and with the other hand, the valve 29 can be opened to cause the passage of fluid through the pipe 14 to discharge the dirt from the spout 11 into the pit 13.

The jet tubes 21 which lead upwardly 10 cause the cooling of the dirt while it is falling into the spout 11, the other of the jet tubes serving to further cool the dirt and to force it out of the spout 11 into the pit 13.

By the arrangement illustrated, I provide means which will efficiently perform the function above described and the combustion chamber can be kept free of dirt which would otherwise prevent the proper operation of the furnace. The dirt which 20 is discharged into the pit 13 can be easily removed and the accumulation of the dirt within the pit does not in any way interfere with the proper operation of the furnace.

25 While I have described my invention as taking a particular form, it will be understood that the various parts of my invention may be changed without departing from the spirit thereof, and hence I do not limit 30 myself to the precise construction set forth, but consider that I am at liberty to make such changes and alterations as fairly come within the scope of the appended claims.

Having thus described my invention, 35 what I claim as new and desire to secure by Letters Patent is:

1. The combination with a furnace having a combustion chamber, of a downwardly extending spout having one end registering 40 with the bottom of the combustion chamber and extending downwardly, said spout being curved within its length and tapering toward its lower end, a pit formed adjacent the lower end of the spout and with which 45 the latter communicates, means for applying fluid under pressure into said spout, means for directing the fluid downwardly within said spout, and a door for closing said spout to the pit, substantially as described.
- 50 2. The combination with a furnace having a combustion chamber, of a downwardly extending spout having one end registering with the bottom of the combustion chamber and curved throughout its length, a pit 55 formed adjacent the lower end of the spout and with which the latter communicates,

means for supplying fluid under pressure into said spout, means for directing the fluid upwardly and downwardly within said spout, and a door for closing said spout to 60 the pit and to the combustion chamber, substantially as described.

3. The combination with a furnace having a combustion chamber, of a spout having an end opening into the bottom of the combustion chamber and extending downwardly therefrom, a pit formed at the opposite end of said spout, a door for closing the said spout to the pit and to the combustion chamber, a pipe surrounding said 70 spout, a supply pipe communicating with said surrounding pipe, branch pipes leading from said surrounding pipe, and jet tubes leading from said branch pipes and communicating with the interior of the spout, 75 substantially as described.

4. The combination with a furnace having a combustion chamber, of a spout having an end opening into the bottom of the combustion chamber and extending downwardly 80 therefrom, a pit formed at the opposite end of said spout, a door for closing the said spout to the pit and to the combustion chamber, a pipe surrounding said spout, a supply pipe communicating with said surrounding 85 pipe, branch pipes leading from said surrounding pipe, jet tubes leading from said branch pipes, certain of said jet tubes pointing downwardly toward the outlet end of the spout while others of said jet tubes point 90 upwardly, substantially as described.

5. The combination with a furnace having a combustion chamber, of a spout having an end opening into the bottom of the combustion chamber and extending downwardly 95 therefrom, a pit formed at the opposite end of said spout, a door slidably mounted adjacent the lower end of said spout and adapted to close the spout to the pit and to the combustion chamber, a lever outside of 100 said furnace, and a link connecting said lever with the door whereby the door is moved when the lever is actuated, substantially as described.

In testimony whereof I have signed my 105 name to this specification in the presence of two subscribing witnesses.

WILLIAM KANE.
